[57] CLAIM

The ornamental design for a extensible stabilizer for attachment to a bass drum lug wing nut and drummer's stool leg or the like, substantially as shown.

DESCRIPTION

FIG. 1 is a side elevational view of a extensible stabilizer for attachment to a bass drum lug wing nut and drummer's stool leg or the like showing my new design;
FIG. 2 is a left side elevational view;
FIG. 3 is a right side elevational view;
FIG. 4 is a bottom plan view; and
FIG. 5 is a top plan view.
